(57) **CLAIM**

The ornamental design for a fixture for aerosol spray container, as shown and described.

DESCRIPTION

FIG. 1 is a front elevational view of a fixture for aerosol spray container, showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a perspective view thereof; and,

FIG. 7 is a perspective view of the fixture for aerosol spray container in use.

The broken lines illustrate environmental structure only and form no part of the claimed design.
